US00D848370S

(12) **United States Design Patent** (10) **Patent No.:** **US D848,370 S**
Lee et al. (45) **Date of Patent:** **** May 14, 2019**

(54) **RADIO FREQUENCY CONNECTOR**

(71) Applicant: **GIGALANE CO., LTD.**, Hwaseong-si
(KR)

(72) Inventors: **Jin Uk Lee**, Hwaseong-si (KR); **Sang Min Seo**, Hwaseong-si (KR); **Hwa Yoon Song**, Hwaseong-si (KR); **Chang Hyun Yang**, Hwaseong-si (KR); **Kyung Hun Jung**, Hwaseong-si (KR); **Hwang Sub Koo**, Hwaseong-si (KR); **Hyun Je Kim**, Hwaseong-si (KR); **Hee Seok Jung**, Hwaseong-si (KR)

(73) Assignee: **GigaLane Co., Ltd.**, Hawseong-si,
Gyeonggi-do (KR)

(**) Term: **15 Years**

(21) Appl. No.: **35/504,589**

(22) Filed: **Sep. 12, 2017**

(80) **Hague Agreement Data**

Int. Filing Date: **Sep. 12, 2017**

Int. Reg. No.: **DM/099354**

Int. Reg. Date: **Sep. 12, 2017**

Int. Reg. Pub. Date: **Mar. 16, 2018**

(30) **Foreign Application Priority Data**

Mar. 15, 2017 (KR) 30-2017-0012138

(51) **LOC (11) Cl.** **13-03**

(57) **CLAIM**

The ornamental design for a radio frequency connector, as shown and described.

DESCRIPTION

1. Radio frequency connector

1.1 : Perspective

1.2 : Front

1.3 : Back

1.4 : Left

1.5 : Right

1.6 : Top

(Continued)

1.7 : Bottom

1.8 : Reference

The reproduction 1.8 is a reference view showing a state in use in which other electric components are combined inside the claimed design; the broken lines illustrating other electric components form no part of the claimed design.

1 Claim, 8 Drawing Sheets
